UNITED STATES PATENT OFFICE.

SVAN NORDEN, OF PROVIDENCE, RHODE ISLAND, ASSIGNOR TO FREDERICK A. STEVENS, OF PROVIDENCE, RHODE ISLAND.

EYEGLASSES.

1,073,777.

Specification of Letters Patent. Patented Sept. 23, 1913.

Application filed June 24, 1912. Serial No. 705,869.

To all whom it may concern:

Be it known that I, SVAN NORDEN, a citizen of the United States, residing at Providence, in the county of Providence and State 5 of Rhode Island, have invented certain new and useful Improvements in Eyeglasses, of which the following is a specification.

My invention relates to eyeglasses, and more particularly to that type commonly 10 known as finger piece structures wherein the nose engaging members are pivotally mounted at either side of the comparatively rigid bridge.

The objects of my invention are to 15 strengthen the action of the guards, at the same time insuring a maximum durability and compactness of structure of the actuating agent or spring which is of advantage in the action and appearance of the mounting parts.

The spring members of eyeglasses, in order to be effective, must be made of metals of so hard a character as to soon crystallize and become brittle, particularly if the 25 spring member comprises but a few coils, as is the case with the present spring members, such as volute springs and helical springs. In the latter two springs it would be essential, in order to secure a proper length of 30 spring to overcome the trouble that the depth of coils of the helical spring, or the outer diameter of the coils of the volute spring, be increased to such an extent as to be unsightly and to interfere with the adjacent parts of the mounting frame.

To the end of overcoming the above disadvantages my invention consists in such parts and combinations of parts as fall within the scope of the appended claims.

Figure 1 is a front elevation of a pair of eyeglasses embodying this invention, Fig. 2, a plan view of one of the guards and the parts adjacent thereto, Fig. 3, a section on line $x-x$ of Fig. 2, Figs. 4 and 5 are plan and side elevations respectively of the spring member, and Fig. 6, a section of the same on line $y-y$ of Fig. 4.

Like reference characters indicate like parts throughout the views.

In the drawings, 1 represents the lenses carried by a support comprising the lens attaching perforated lugs 3 and the vertical bearing lugs 4. The former lugs are attached by the usual screws 5. An arched 55 and comparatively rigid bridge 6 connects

the lens attaching devices through horizontal connecting or supporting portions 7. Upon the portion 7 is a pivot member of any usual construction. In the present instance it consists of an integral interiorly 60 threaded hollow post 10 extending upwardly, and a similar post 12, extending downwardly, from the support 7 in alignment with each other. In the post 10 is the shank 14 of a screw provided at its end 65 with a head 15 in contact with the end of the post and of greater diameter than the post. The threaded shank 17 of a second screw is engaged in the threaded post 12; this screw carries a head 19 contacting with 70 the end of the post and overlapping the operating arm 21 mounted to swing upon the post or pivot 12 which passes loosely through an opening 22 in the arm.

My novel spring member 24 rests upon the 75 support 7, and around the post 10, and in contact with the screw head 15. It will be understood that the positions of the arm 21 and spring member 24 may be reversed, and that any form of post or pivot may be employed, or the shank of a screw alone may be used as a post, without departing from the spirit of my invention.

The guard arm in the present instance terminates, at its rear end, in a nose bearing 85 portion 26; and at its forward end, in the operating lug 27.

The spring 24 is made from a single piece of resilient metal preferably substantially cylindrical or oval in cross section, and 90 comprises an upper coil or convolution 30 terminating in an arm 31 and merging into a second coil 32 of less diameter than the coil 30, and located in substantially the same plane and continued downwardly to form a 95 third coil 33 of substantially the same diameter merging into a fourth coil 34 which lies in substantially the same plane as the coil 33 and is of substantially the same diameter as the coil 30, and terminates in an 100 arm 36. It will be observed that the coils 30 and 33 lie in substantially parallel planes, nearly contiguous to each other, occupying a minimum of space in a vertical direction, and that a maximum of strength 105 is imparted to the entire spring member by the two central coils 32 and 33 of reduced diameter, the latter two coils not only compensating for the more diffused character of the upper and lower coils, but without ap- 110

preciablely increasing the vertical dimensions of the spring member. Thus a minimum of area is exposed to the eye of the observer, and there is combined in the single member 5 all the advantages inherent in a flat spiral or volute spring and a helical spring without the disadvantages of either of the latter forms, and of a construction permitting a maximum of material in a minimum of 10 space.

The arm 31 in the present instance bears against the lug 4 of the lens attaching device, while the arm 36 engages the rear portion of the operating arm 21 at a point behind the post 10. The spring member 24 normally presses the nose bearing portion or 15 pad 26 inwardly against the surface of the nose, and the arms 21 are operated through the members 27 by the thumb and finger in the usual manner employed in this type of 20 eyeglasses.

What I claim is,—

1. In an eyeglass mounting, the combination with a support, and a nose guard pivotally mounted thereon, of a coil spring for 25 positioning the guard having its axis coincident with the turning axis of the guard, said spring comprising coils one within the other upon opposite sides of the central portion of the spring, the coils upon one side extending in a direction opposite to those on the other side of said central portion.

2. In an eyeglass mounting, a coil spring for positioning the guard having its axis coincident with the turning axis of the guard, 35 said spring having inner and outer coils of different diameters and a connecting portion intermediate the inner and outer coils intermediate the ends of the spring.

3. A spring for finger piece eyeglass guards comprising two superposed flat spiral coils formed from a single continuous strip of material.

4. A spring for finger piece eyeglass guards comprising two superposed flat spiral coils having portions of their respective inner convolutions integrally connected together.

5. A spring for finger piece eyeglass guards comprising two superposed flat spiral coils, the inner end of each coil being connected to that of the other and the outer end of each being free.

6. A spring for finger piece eyeglass guards comprising two superposed flat spiral coils formed from a single continuous

strip of material and lying in contact with each other.

7. A spring for finger piece eyeglass guards comprising a flat spiral coil having 60 its inner convolution continued laterally of the plane of the coil and thence looped in substantial parallelism to such plane to produce a further resilient portion and bringing the extremity of the spring strip toward 65 the outer periphery of the coil whereby both ends of the spring are exteriorly arranged for purposes of attachment.

8. In a finger piece eyeglass mounting, the combination with a support, a guard lever arranged to turn thereon, and a post on one of said parts, of a spring for positioning the guard comprising two superposed flat spiral coils surrounding the post as a centering projection and formed of a single 75 strip of resilient material having one end acting against the guard and the other against the support.

9. In a finger piece eyeglass mounting, the combination with a support, a guard lever 80 arranged to turn thereon and a post on one of said parts, of a spring for positioning the guard comprising two superposed flat spiral coils wound in opposite directions about the post as a centering projection, the coils 85 being joined together at points on their respective inner convolutions and having their outer convolutions acting against the guard and support, respectively.

10. In an eyeglass mounting, the combination with a support, a guard lever arranged to turn thereon and a post on one of said parts, of a spring for positioning the guard comprising a flat spiral coil surrounding the post as a centering projection, the 90 outer convolution thereof being arranged to act against one of said first mentioned parts and the inner convolution being continued laterally of the plane of the coil and thence looped in substantial parallelism to such 95 plane to produce a further resilient portion and bringing the extremity of the spring strip toward the outer periphery of the coil for attachment to the other of said first mentioned parts.

In testimony whereof I have affixed my signature in presence of two witnesses.

SVAN NORDEN.
